(57) CLAIM

The ornamental design for a home theater, as shown and described.

DESCRIPTION

FIG. 1 is a front, right side, perspective view of a home theater showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines indicate unclaimed portions and form no part of the claimed design.
